(57) **CLAIM**

The ornamental design for a stroller accessory, as shown in the accompanying drawings and described above.

DESCRIPTION

FIG. 1 is a front, top, right perspective view of a stroller accessory in accordance with the present invention;

FIG. 2 is a rear, bottom, left perspective view of the stroller accessory of FIG. 1;

FIG. 3 is a right elevation view of the stroller accessory of FIG. 1;

FIG. 4 is left elevation view of the stroller accessory of FIG. 1;

FIG. 5 is a front elevation view of the stroller accessory of FIG. 1;

FIG. 6 is a rear elevation view of the stroller accessory of FIG. 1;

FIG. 7 is a top plan view of the stroller accessory of FIG. 1; and,

FIG. 8 is a bottom plan view of the stroller accessory of FIG. 1.

The broken lines shown herein are for illustrative purposes and form no part of the claimed design. For example, the broken lines in the form of an alternating series of relatively short dashes and relatively long dashes represent bounds of the claimed design.
